UNITED STATES PATENT OFFICE

135,138

DESIGN FOR A COMPASS

Floyd G. Eubanks, Pasadena, Calif., assignor of forty-seven and one-half per cent to Francis E. Vaughan, Pasadena, and five per cent to Robert M. McManigal, Compton, Calif.

Application May 12, 1941, Serial No. 100,903

Term of patent 14 years

To all whom it may concern:

Be it known that I, Floyd G. Eubanks, a citizen of the United States, residing at Pasadena, in the county of Los Angeles and State of California, have invented a new, original, and ornamental Design for a Compass, of which the following is a specification, reference being had to the accompanying drawing, forming part thereof.

Figure 1 is a perspective view of a compass showing my new design;

Figure 2 is a front elevational view of the same; and

Figure 3 is a side elevational view thereof.

The characterizing feature of my design for the compass shown resides in the specific open construction of the legs thereof as particularly illustrated in Fig. 3 of the drawing.

I claim:

The ornamental design for a compass, as shown and described.

FLOYD G. EUBANKS.
